CLAIM

The ornamental design for an animal shelter, as shown and described.

DESCRIPTION

FIG. 1 is a bottom-rear isometric view of an animal shelter showing the new design;

FIG. 2 is a top-rear isometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines show portions of the animal shelter that form no part of the claimed design.
